UNITED STATES PATENT OFFICE.

GEORGE FRANKLIN VAN BRUNT, OF KEWANEE, ILLINOIS.

WATER-ELEVATING APPARATUS.

1,246,188.

Specification of Letters Patent. Patented Nov. 13, 1917.

Application filed October 25, 1916. Serial No. 127,581.

To all whom it may concern:

Be it known that I, GEORGE FRANKLIN VAN BRUNT, a citizen of the United States, residing at Kewanee, in the county of Henry 5 and State of Illinois, have invented certain new and useful Improvements in Water-Elevating Apparatus, of which the following is a full, clear, concise, and exact description.

- 10 This invention relates to apparatus for elevating fluids from one level to another, and more particularly to such apparatus for elevating water from a well, cistern or other receptacle to outlet points variously located.
- 15 The object of this invention is the provision of an efficient self-contained fluid elevating apparatus of few parts, readily and easily assembled.

In accordance with the present invention, 20 there is provided a cylinder having a fluid inlet and within which is a floating reservoir. The cylinder is provided with a fluid outlet pipe having communication with the floating reservoir, and with air inlet and 25 exhaust valves controlled by the floating reservoir.

For a more complete understanding of 20 this invention, reference should be had to the following description, taken in connection with the drawings, wherein:

Figure 1 shows a longitudinal cross-sectional view of the fluid elevating apparatus containing one embodiment of the present invention;

Fig. 2 is a perspective of the air inlet and exhaust valves and their connections to the floating reservoir;

Fig. 3 is a sectional view on line 3—3 of Fig. 1, showing roller guides for the floating 40 reservoir;

Fig. 4 is a sectional view in line 4—4 of Fig. 1, showing a system of roller supports for a system of auxiliary weights which co-operate with the floating reservoir in the 45 control of the air inlet and exhaust valves;

Fig. 5 is a sectional view on line 5—5 of Fig. 1, showing the position of the weights when the floating reservoir is practically empty and in its raised position;

Fig. 6 is a view showing the position of the weights when the floating reservoir is full and in its lowered position; and

Fig. 7 is a view showing how the roller guides for the weights are mounted.

Referring to the drawings, the cylinder 55 may comprise a metal tube 10, in the lower

end of which is a foot valve 13, securely attached thereto by means of a threaded bushing 12 and an internally threaded ring 11. The foot valve 13 serves as a fluid inlet for 60 the cylinder. In order that there may be a tight fit when the valve is seated, a packing ring, preferably of leather, may be provided. The upper end of the cylinder is closed by means of a head 15, secured to the 65 pipe 10 by means of an internally threaded ring 16. The head 15 is provided with three openings, an air inlet 17, to the upper end of which is attached a pipe 20, leading to a supply of compressed air, an air exhaust 18 70 and a fluid outlet 19, to the upper end of which is attached a pipe 21, leading to any desired location.

An air inlet valve 25 of the ball type fits 75 into the lower end of the opening 17, and an exhaust valve 26 fits into the lower end of the opening 18. A valve lever 29, to one end of which is pivoted an arm 31 for controlling the ball 32 of the inlet valve 25, is pivotally mounted in the lower end of a 80 downwardly extending arm 27, formed integrally with the body of valve 25. A similar valve lever 30, to one end of which is pivoted the valve face 33 of the exhaust valve 85 provided with a rod 34 for guiding valve face 33 to its seat, is pivotally mounted in the lower end of a downwardly extending arm 28, formed integrally with the body of exhaust valve 26. The inner or free ends of the valve levers 29 and 30 are U-shaped and 90 pass through openings in a yoke piece 35, so that vertical movement of the yoke 35 imparts a simultaneous movement to the valve levers 29 and 30 for opening one valve and closing the other.

Within the cylinder there is provided a can 40 which, in the operation of the apparatus, is adapted to rise and fall and to be filled with and emptied of a fluid, thereby 100 serving as a floating reservoir. To the upper edge of and on the inside of the can 40 are attached two rings or bails 39, upon each of which is mounted an upwardly extending slotted member 41. Within the slots of the members 41 slide the ends of the 105 yoke 35. The construction of the slotted members 41 and the ends of the yoke 35 is such that the can 40 may rise or fall for a considerable distance without affecting the position of the yoke 35, and therefore the 110 air inlet and exhaust valves. The legs of the U-shaped end of valve lever 30 extend

to points immediately over the edge of the can 40, so that when the can has risen sufficiently, the rings 39 attached thereto engage the extreme ends of those legs to start the 5 movement of valve lever 30 about its pivot point to open the exhaust valve.

Into the lower end of the fluid outlet opening 19 is secured a fluid outlet pipe 42, which extends through an opening in the yoke 35 10 down into the can 40, terminating at a point near the bottom thereof when the can is in its raised position, as shown in full lines in Fig. 1. Upon the outlet pipe 42 are mounted two spiders 43, one near the top 15 and the other near the bottom, upon the ends of the arms of which are mounted rollers 44 for guiding the floating reservoir.

In order to assist the floating reservoir 40 in the control of the air inlet and exhaust 20 valves, there is provided a system of weights, which in the operation of the fluid elevating apparatus are alternately supported by the floating reservoir and by the outlet pipe. This system of weights may be made up of 25 sets of six balls 45. The means of supporting each set is the same and is such that in the downward movement of the floating reservoir 40, the balls are shifted from a support on the fluid outlet pipe 42 to a support moving 30 with the reservoir 40, and in the upward movement of the reservoir, the balls are shifted back onto the support on the fluid outlet pipe 42. The support for each set of balls on the fluid outlet pipe 42 may 35 consist of a plate 50, secured to the pipe 42, supporting near its periphery six brackets 51 upon each of which is rotatably mounted a roller 52. Each roller 52 supports a ball 45 when the reservoir 40 is in its raised position, as shown in Fig. 1. The series of plates 40 50 are supported at the peripheries thereof by means of vertical strips 53 which also serve to coöperate with the rollers 52 and pipe 42 to provide individual compartments 45 for the balls 45. For each set of balls, there is provided a ring 54, supported by the rings 39 on the reservoir 40. The rings 54 are spaced apart and supported by means of vertical strips 55 which are securely attached 50 to the rings or bails 39. Each ring 54 at its inner periphery is provided with a downwardly extending flange 56 against which the balls may rest when the reservoir 40 is in its raised position. The distance 55 between the flange 56 and the center line of each roller 52 is greater, and the distance between the outlet pipe 42 and the center line of each roller 52 is less, than the radius of the balls 45 so that in the position of the 60 reservoir, shown in Fig. 1, the balls 45 will be supported by the rollers 52 and will rest against the flange 56. If the reservoir is lowered, as when filled with a fluid, the rings 54 will move downward to a point below 65 the horizontal center line of the rollers

52, whereupon the balls 45 roll onto the rings 54 and rest against the rollers 52, as shown in Fig. 6. The combined weight of the balls 45 is such that with the balls on the rings 54 and the reservoir in its lower position, as shown by the dotted lines in Fig. 1, it will be held there until the level of fluid in the reservoir 40 has reached a point just above the lower end of the outlet pipe 42, when the buoyancy of the reservoir will 70 overcome the weight of the balls 45 and it will rise. As the reservoir 40 gradually rises, the balls 45 are transferred to the rollers 52, whereupon the reservoir 40 continues to rise at a more rapid rate, finally raising 75 the yoke 35 and operating the valve levers 29 and 30 to open the exhaust valve and to close the air inlet valve.

The fluid inlet or foot valve 13 is large 80 compared to the area between the reservoir 40 and the side of the cylinder, so that when a fluid is being admitted through the inlet valve 13 and while the fluid is rising around the reservoir and flowing into it at its top, the reservoir 40 will be supported in its 85 raised position until filled with the fluid.

Let it be assumed that the elevating apparatus hereinbefore described is installed, so that the cylinder is immersed in water or some other fluid to a depth such that the top 90 of the reservoir 40 is slightly below the level of the water, but as yet no supply of compressed air is connected with the pipe 20. Under these circumstances, the reservoir 40 will be in its lowered position, and water 100 will force open the foot valve 13, admitting water to the cylinder. As water rises in the cylinder, it will, before rising to the top of the reservoir 40, reach a point at which the buoyancy of the reservoir overcomes the 105 weight of the balls 45, when the reservoir will rise, transferring the balls to the rollers 52, and opening the exhaust valve and closing the air inlet valve. The water will continue to rise until it reaches the top of the 110 reservoir 40 into which it will flow until the reservoir 40 is filled, when the reservoir 40 will sink, closing the exhaust valve and opening the air inlet valve, the balls 45 being transferred from the rollers 52 to the 115 rings 54. If at this time a source of compressed air be connected with the pipe 20 when the water pipe 21 is closed at its outer end, the only result will be the closure of the foot valve 13 brought about by the pressure 120 of the compressed air within the cylinder. Now if the water pipe 21 be opened, the air pressure in the cylinder will force water up through the water outlet pipe 42, opening 19 and water pipe 21. Water will continue to 125 flow as long as pipe 21 is open. When the level of the water in the reservoir 40 reaches a point slightly above the lower end of water outlet pipe 42, the buoyancy of the 130 reservoir overcomes the weight of the balls

45, and the reservoir begins to rise. When it has risen far enough to permit its upper edge to engage the extremities of the U-shaped end of the valve lever 30, the transference of the balls 45 from the rings 54 to the rollers 52 has proceeded to such an extent that the most of the weight is supported by the rollers. The reservoir, therefore, now rises very rapidly, moving the 5
10 valve levers 29 and 30 about their pivot points to close the air inlet valve and open the exhaust valve. The air inlet being closed and the exhaust open, the pressure of the water in which the cylinder is immersed 15 forces the foot valve open, and the reservoir is again filled. When filled, the reservoir sinks, closing the exhaust valve and opening the air inlet valve as before explained, whereupon the foot valve 13 is closed, since 20 a source of compressed air is connected with pipe 20.

To prevent water in the water outlet pipe 42 from pouring back into the reservoir while the reservoir is being filled, an ordinary check valve 60 may be placed in the water outlet pipe 42 near its lower end.

In the appended claims, whenever the terms, a water elevating apparatus, a water inlet or inlet valve, and a water outlet pipe 80 are used, it is to be understood that such terms do not limit the claims to an apparatus for elevating water, for it is clearly within the scope of this invention to employ such apparatus for elevating other fluids.

85 The invention claimed is:

1. In a liquid elevating apparatus, in combination, a liquid compartment having a liquid inlet valve, a floating reservoir within the compartment free to rise and fall 40 therein, a liquid delivery pipe for the compartment having communication with the floating reservoir, air inlet and exhaust valves for the compartment, and accelerating mechanism within the compartment operated by a predetermined rise or fall of the floating reservoir to cause the more rapid movement of the floating reservoir thereby to control the air inlet and exhaust valves.

45 2. In a liquid elevating apparatus, in combination, a liquid compartment having a liquid inlet valve, a floating reservoir within the compartment free to rise and fall therein, a liquid delivery pipe for the compartment having communication with the floating reservoir, air inlet and exhaust valves for the compartment, and auxiliary mechanism within the compartment rendered operative when the floating reservoir has moved for a predetermined distance to 55 cause the more rapid movement thereof whereby the air inlet and exhaust valves are controlled.

60 3. In a water elevating apparatus, in combination, a stationary submerged cylinder having a water inlet valve, a floating

reservoir within the cylinder, a water outlet pipe for the cylinder having communication with the floating reservoir, air inlet and exhaust valves for the cylinder, and a weight within the cylinder cooperating with 70 the floating reservoir to control the air inlet and exhaust valves.

4. In a water elevating apparatus, in combination, a stationary submerged cylinder having a water inlet valve, a floating 75 reservoir, a water outlet pipe for the cylinder having communication with the floating reservoir, air inlet and exhaust valves for the cylinder, and a system of movable weights, alternately supported by the floating reservoir and by the stationary cylinder, cooperating with the floating reservoir to control the air inlet and exhaust valves.

5. In a water elevating apparatus, in combination, a stationary submerged cylinder having a water inlet valve, a floating reservoir within the cylinder, a water outlet pipe for the cylinder having communication with the floating reservoir, air inlet and exhaust valves for the cylinder, and a 80 system of weights, alternately supported by the floating reservoir and by the water outlet pipe, cooperating with the floating reservoir to control the air inlet and exhaust valves.

95 6. In a water elevating apparatus, in combination, a stationary submerged cylinder having a water inlet valve, a floating reservoir within the cylinder, a water outlet pipe for the cylinder having communication with the floating reservoir, air inlet and exhaust valves for the cylinder, and a plurality of weights, supported by the floating reservoir when filled with water and by the water outlet pipe when the reservoir is empty and 100 cooperating with the floating reservoir to control the air inlet and exhaust valves.

105 7. In a water elevating apparatus, in combination, a stationary submerged cylinder having a water inlet valve, a floating reservoir within the cylinder, a water outlet pipe for the cylinder extending down into the floating reservoir, air inlet and exhaust valves for the cylinder, suitable levers connecting the floating reservoir and the air 110 inlet and exhaust valves, and a plurality of weights supported by the outlet pipe while the reservoir is being filled and transferred to and assisting the filled reservoir to close the exhaust and open the air inlet valve.

115 8. In a water elevating apparatus, in combination, a stationary submerged cylinder having a water inlet valve, a floating reservoir within the cylinder, a water outlet pipe for the cylinder extending down into the floating reservoir, air inlet and exhaust valves for the cylinder, suitable levers connecting the floating reservoir and the air inlet and exhaust valves, and a plurality of weights supported by the floating reser- 125

voir while it is being emptied and transferred to the outlet pipe as the empty reservoir begins to rise to permit the rising empty reservoir to simultaneously close the air inlet and open the exhaust valve.

9. In a water elevating apparatus, in combination, a stationary cylinder having a foot valve at one end for admitting water to the cylinder, a head for the other end of the cylinder, air inlet and exhaust valves in the head, a floating reservoir within the cylinder, a water outlet pipe for the cylinder supported by the head and extending down into the floating reservoir, pivoted valve levers and a yoke supported by the head and forming connections between the floating reservoir and the air inlet and exhaust valves, and a system of movable weights, alternately supported by the floating reservoir and by the water outlet pipe, coöperating with the floating reservoir to actuate the valve levers for controlling the air inlet and exhaust valves.

10. In a water elevating apparatus, in combination, a cylinder having a water inlet, a floating reservoir within the cylinder, a water outlet pipe for the cylinder extending down into the floating reservoir, air inlet and exhaust valves for the cylinder, two levers, one for the air inlet valve and the other for the exhaust valve, pivotally supported by the cylinder, a yoke engaged by the floating reservoir and coöperating with the two levers to control the air inlet and exhaust valves, and a weight, alternately supported by the floating reservoir and by the water-outlet pipe, for aiding the floating reservoir in controlling the air inlet and exhaust valves.

11. In a water elevating apparatus, in combination, a stationary cylinder having a foot valve at one end for admitting water to the cylinder, a head for the other end of the cylinder, air inlet and exhaust valves in the head, a floating reservoir within the cylinder, a water outlet pipe for the cylinder supported by the head and extending down into the floating reservoir, valve levers for the air inlet and exhaust valves pivotally supported by the head, a yoke normally supported by the valve levers and engaged by the floating reservoir for actuating the valve levers to control the air inlet and exhaust valves, and a member, alternately supported by the floating reservoir and the water-outlet pipe, for aiding the floating reservoir in controlling the air inlet and exhaust valves.

12. In a water-elevating apparatus, in combination, a floating reservoir, a water inlet valve, air-inlet and exhaust valves associated therewith, a water-outlet pipe having communication with the floating reservoir, and auxiliary mechanism within the floating reservoir rendered operative upon a predetermined movement of the floating

reservoir to cause the more rapid movement thereof for controlling the air inlet and exhaust valves.

13. In a liquid elevating apparatus, in combination, a liquid compartment having a liquid inlet valve, a floating reservoir within the compartment free to rise and fall therein, a liquid delivery pipe for the compartment having communication with the floating reservoir, air inlet and exhaust valves for the compartment, and auxiliary mechanism within the compartment normally tending to retard the movement of the reservoir and rendered operative thereby to accelerate the movement of the reservoir upon a predetermined movement thereof, thereby to control the air-inlet and exhaust valves.

14. In a water elevating apparatus, in combination, a floating reservoir, a water inlet therefor, air inlet and exhaust valves associated therewith, a water outlet pipe having communication with the floating reservoir, and a system of weights within the reservoir coöperating therewith to control the air inlet and exhaust valves.

15. In a water elevating apparatus, in combination, a floating reservoir, a water inlet therefor, air inlet and exhaust valves associated therewith, a water outlet pipe having communication with the floating reservoir, and a system of weights within the floating reservoir alternately supported by the reservoir and the water outlet pipe and coöperating with the reservoir to control the air inlet and exhaust valves.

16. In a water elevating apparatus, in combination, a stationary submerged cylinder having a water-inlet valve, a floating reservoir within the cylinder, a water-outlet pipe for the cylinder having communication with the floating reservoir, air-inlet and exhaust valves for the cylinder, and a weight, alternately supported by the floating reservoir and by the water-outlet pipe, coöperating with the floating reservoir to control the air-inlet and exhaust valves.

17. In a water-elevating apparatus, in combination, a stationary submerged cylinder having a water-inlet valve, a floating reservoir within the cylinder, a water-outlet pipe for the cylinder extending down into the floating reservoir, air-inlet and exhaust valves for the cylinder, suitable levers connecting the floating reservoir and the air-inlet and exhaust valves, and a weight supported by the outlet pipe while the reservoir is being filled and transferred to and assisting the filled reservoir to close the exhaust and open the air-inlet valves.

18. In a water-elevating apparatus, in combination, a stationary submerged cylinder having a water-inlet valve, a floating reservoir within the cylinder, a water-outlet pipe for the cylinder extending down into the floating reservoir, air inlet and exhaust valves

valves for the cylinder, suitable levers connecting the floating reservoir and the air-inlet and exhaust valves, and a weight supported by the floating reservoir while it is being emptied and transferred to the outlet pipe as the empty reservoir begins to rise to permit the rising empty reservoir to si-

multaneously close the air-inlet and open the exhaust valve.

In witness whereof, I hereunto subscribe my name this 20th day of October, A. D., 1916.

GEORGE FRANKLIN VAN BRUNT.
